(57) CLAIM

The ornamental design for ceiling mounted swing arm lamp, as shown and described.

DESCRIPTION

FIG. 1 is a prospective view of a ceiling mounted swing arm lamp of the present invention;

FIG. 2 is a front elevational view thereof;

FIG. 3 is a rear elevational view thereof;

FIG. 4 is a top plan view thereof;

FIG. 5 is a bottom view thereof;

FIG. 6 is a left side view thereof;

FIG. 7 is a right side view thereof;

FIG. 8 is a prospective view of an alternative embodiment of the ceiling mounted swing arm lamp;

FIG. 9 is a front elevational view of the lamp shown in FIG. 8;

FIG. 10 is a rear elevational view thereof;

FIG. 11 is a top plan view thereof;

FIG. 12 is a bottom view thereof;

FIG. 13 is a left side view thereof; and,

FIG. 14 is a right side view thereof.

The broken lines shown on the drawings are for illustrative purposes only and form no part of the claimed design.
